CHARLES ALVIN STEWART, OF HIGHLANDS, NEW YORK.

CRATE

1,373,271.

Specification of Letters Patent. Patented Mar. 29, 1921.

Application filed February 26, 1920. Serial No. 361,535.

To all whom it may concern:

Be it known that I, CHARLES A. STEWART, a citizen of the United States, and a resident of Highlands, in the county of Ulster and State of New York, have invented a new and improved Crate, of which the following is a full, clear, and exact description.

It is well understood that one of the most difficult articles to properly crate is fresh fruit, and particularly where such fruit is packed in the conventional packing baskets which are crowded together into a crate for the purpose of shipment.

Even where these baskets have been properly crated, the crate itself is a very cumbersome object to handle, and due to the haste and carelessness of expressmen, the crates are liable to be carelessly packed in a freight car so that certain of the same are lying sideways, others are properly placed, and still others are placed upon their top ends.

With the above in view I have constructed a crate which is intended for the packing of fruit, and more particularly adapted to receive the individual baskets of the same, commonly known as grape baskets. A crate constructed in accordance with my invention permits of a packing of grape baskets in a particularly compact manner, whereby a minimum of space is utilized and the packing crates are not subjected to as rough a handling as is the case with larger receptacles.

A still further object of my invention is the construction of a crate which will provide a handle to facilitate the handling thereof, and which handle will at all times serve to prevent danger of the crates being placed wrong side up as is now the case.

Further objects of the invention are the construction of a crate of unusual simplicity permitting of extreme economy in manufacture, as well as other objects which will become more apparent upon an examination of the subsequent specification and appended drawings, which latter represent practical embodiments of my invention, and in which—

Figure 1 is an elevational view of one form of crate constructed in accordance with my invention.

Fig. 2 is a sectional side view thereof.

Fig. 3 is a sectional plan view thereof.

Fig. 4 illustrates a second form of crate

constructed in accordance with my invention, and is a sectional side view therethrough.

Fig. 5 is a plan view of the same.

In all of these views like reference numerals designate similar parts and the reference numeral 6 indicates side planks, to the ends of which are attached top and bottom sections 7, each forming two parts, as has been indicated by the reference numeral 8 in Fig. 1. Baskets such as 9 are arranged in pairs, one on top of the other, the next over and under lying pair of baskets extending transversely to the intermediate pair by means of which, as has been clearly indicated in Fig. 2, the handles 10 of each pair of baskets extend upwardly between the next overlying pair. By virtue of the split portion or slot 8 formed between the half-sections of the upper and lower ends of the crate, the handles of the uppermost pair of baskets are permitted to extend beyond the upper end of the crate thus serving as a handle for the latter. As has been clearly shown in Fig. 3 certain portions of the ends of the baskets of each row overlie one another, and these present a neat and compact portion entirely filling out the space between the side member 6 of the crate.

It will be noted upon examination, that the crate illustrated in Figs. 1, 2 and 3 is of extreme simple construction in that the same includes merely eight parts and it will readily be apparent that a crate of this nature is primarily constructed with a complete lower end portion, three side planks 6, and one of the upper end portions 7. In other words, one of the side planks 6 and the portions 7 of the upper end of the crate to which it is attached are removed. A pair of baskets is now arranged upon the lower end of the crate, and further pairs properly positioned in the manner afore described, placed upon the same, care being taken that the uppermost pair of baskets 9 are arranged with their tops transversely to the slit portions 8 so that handles 10 may project through the same and serve as a medium by means of which the crate may readily be grasped and carried.

It is now often desirable, where a crate embodying the spirit of my invention is to be constructed; that such crate be formed in a most economical manner, and with a

view of providing this construction I have formed a crate in the manner illustrated in Figs. 4 and 5 in which oppositely disposed side planks 6 are attached to one another adjacent their upper and lower ends, by pairs of spaced slats 11. The second pair of opposed side planks are attached to the body of the crate by top and bottom pieces 12, which have their inner ends secured to the slats 11.

It will now be seen, in connection with the last described type of crate, that one of the side planks and its associated top piece are removed from the body of the crate, and the same is filled in the usual manner with pairs of baskets 9. The handles of the uppermost pair of baskets are brought to a position bearing against the inner face of one of the slats 11, and the removed side plank and its associated top piece 12 are now moved into applied position, so that the baskets are held within the body of the crate.

Obviously, numerous modified structures of crate might be made without departing from the scope of my invention, in that a pair of spaced members are provided in both of the ends of the crate so that the handles of the uppermost pair of baskets may project through the space thus afforded, and serve as a handle for the crate. In this connection it is to be borne in mind that an extremely simple form of construction is provided by means of my invention in that it is merely necessary to remove one of the side planks and top portions of the crate, which may thereupon be filled and to

subsequently apply the removed portions of the crate to the body of the same.

I claim:

1. A crate, including two units, one of said units comprising side planks, and a plurality of end sections, the second unit including a side plank and an end section, said crate being adapted to receive baskets formed with handles, said baskets being adapted to be arranged upon one another, and to extend transversely of each other, the end section of the second unit being adapted to be spaced from one of the end sections of the first named unit, whereby to provide a slot through which the handles of the uppermost baskets may project to provide a handle for the crate, and means for securing the units forming said crate in applied position.

2. A crate comprising two sections removably joined together, one of said sections including a base, a plurality of upright planks rigidly secured to the base and a top section supported on the upper ends of said planks, the other section comprising a single plank adapted to be rigidly secured at its lower end to the base, a top section rigidly connected to the plank and adapted to be connected to the upper ends of the first-mentioned planks in spaced relationship to the first-mentioned top section, whereby a slot is provided between the adjacent edges of the top sections adapted to accommodate the upwardly extended handles of containers located in the crate.

CHARLES ALVIN STEWART.
